SPRINKLER

Stanley W. Yoder, Los Angeles, Calif.

Application September 15, 1945, Serial No. 616,586

6 Claims. (Cl. 299—114)

1

My invention relates in general to sprinklers and more particularly to the type of sprinklers known customarily as whirlpool sprinklers.

Sprinklers of the whirlpool type are characterized by having the sprinkled fluid, usually water, forced into a rapid rotary motion within a dome and discharged in a spray by centrifugal force rather than by being divided and directed in a spray by small orifices. The orifice on the dome of such a sprinkler is usually provided with a thin lip to achieve greater comminution by suddenly changing the direction of motion from inwardly and rotary to outwardly and tangential. The thin lip presents problems of corrosion and wear and it is not uncommon to have it in the form of a special insert of brass or other nonrusting metal. The whirlpool effect within the dome is obtained by a tangential inlet. However, the water pressure forces the vortex to one side of the exit orifice, and in fact may cause it to move around as such vortices are commonly observed to move in nature, resulting in an elliptical and erratic discharge instead of an even circular spray.

It is accordingly a principal object of my invention to provide a sprinkler of whirlpool action that will throw the spray evenly in all directions.

It is another of my objects to so control and direct the flow of water as to render unnecessary the use of thin lips or noncorrosive inserts.

It is still a further object to provide a sprinkler ruggedly constructed of a minimum of easily manufactured parts.

These and other objects I obtain in a manner which will be clear from a consideration of the following description taken in connection with the accompanying drawings, in which:

Figure 1 is a plan view of my sprinkler;

Figure 2 is a front elevation;

Figure 3 is a side elevation;

Figure 4 is a vertical section of the sprinkler as disposed in Fig. 2, and on an enlarged scale;

Figure 5 is a vertical section on the line 5—5 of Fig. 4; and

Figure 6 is a partial horizontal section on the line 6—6 of Fig. 4, but on the scale of Fig. 1.

Referring now to Figs. 1, 2, and 3, the numeral 10 designates a casing, the central portion of which is curved upwardly to form a round dome 11 with a central orifice 12. A boss 13, carried off center by the dome 11, is recessed and threaded internally, as shown at 14 in Figs. 5 and 6, to receive the end of a hose or other conduit. At the inmost end of the recess is an in-

2

let passage 15, of restricted cross-section relative to the hose or conduit, which connects with the inside of the dome 11 in a tangential manner.

As shown in Figs. 4 and 5, the orifice 12 is provided with an inwardly extending annular flange 16, which I designate as a centralizing tube. This centralizing tube 16 extends inwardly to about the level of the mid-point of the inlet 15. The sides of the dome 11 are extruded inwardly at the point where they outwardly join the casing 10, to form a second annular flange 17 which, as will be seen, serves as a supporting flange.

As also shown in Figs. 4 and 5, a plug 18 is pressed within the supporting flange 17, sealing the bottom of the dome 11. On its interior surface the plug 18 carries an annular ridge or wall 19. The wall 19 is of greater diameter than, and concentric with, the centralizing tube 16, and is of sufficient height to overlap slightly the inner end of the tube 16.

It will be seen from the foregoing that the entire construction is of the utmost simplicity, consisting of two major pieces which may be die-cast and pressed together and requiring machinery only for the threaded connection for the nose.

In operation, the water enters the sprinkler at high velocity through the inlet 15 and is deflected from short-circuiting to the centralizing tube 16 and the orifice 12 by the ridge 19. The water is thereby forced to rotate within the dome 11, and as all parts therein contacted by the water are annular in form and without ports, ribs, or other frictional obstructions, the water develops a high rotational speed.

Since the cross-section of flow in the dome is larger than that of the inlet 15, the velocity is less than that in the inlet, and as is well known in hydrodynamics, such a change of velocity tends to set up internal turbulence and eddies. The presence of the centralizing tube 16 counteracts this tendency and streamlines the rotary flow more evenly than would be otherwise possible. The outflowing water moves evenly downwardly between the annular wall 19 and the centralizing tube 16 which by their overlap prevent the pressure at the inlet 15 from exerting decentralizing force upon the swirling water contained between them. Consequently, the water passes under the lower edge of the centralizing tube 16 with an even distribution around the entire edge, and rises within the tube, clinging to the walls thereof by centrifugal force, to the orifice 12, from the

lip of which it is sprayed evenly in all directions. As the water is not moving inwardly just before it is released for outward spray, it requires no special thin edge to assist in its even distribution, and the simplicity and strength which is a feature of my invention may be maintained.

The annular wall 19 not only prevents the incoming water from passing directly to the rim of the centralizing tube 16, but it also forms with that tube a restricted annular passage, thereby increasing the rotary velocity of the water at that point and causing it to begin its outward travel through the centralizing tube with great speed. The centralizing tube 16 forms a fixed vortex around which the water swirls, preventing the formation of a one-sided or wobbling vortex such as occurs when the vortex is free. When the water passes under the edge of the centralizing tube, it clings to the inner surface of the tube by centrifugal force and is lifted by the water behind it, producing an evenly distributed supply of spray-forming water at the orifice 12.

Other means of forming the chamber and of creating a restricted annular passage to a tubular exist will occur to those familiar with the art and should be understood to come within the scope and spirit of my invention. I wish it to be understood that this detailed description and showing of one embodiment of my invention is not to be taken in a limiting sense, as the invention is best defined in the appended claims.

I claim:

1. A sprinkler comprising a circular chamber, an inlet to said chamber arranged substantially tangentially thereof, an outlet positioned centrally at one end of said chamber, a recess in the other end of said chamber having an annular wall, a tubular flange on said outlet extending within said chamber to a point within said recess, said tubular flange and said annular wall forming between them a restricted annular passage to the interior of said tubular flange.
2. A sprinkler comprising a circular chamber, an inlet to said chamber arranged substantially tangentially thereof, an outlet positioned centrally at one end of said chamber, a tubular flange on said outlet extending centrally within said chamber to a point adjacent the other end thereof, and means forming part of said other end of said chamber for directing the flow of liquid into the interior of said tubular flange at a velocity higher than the mean velocity within the chamber.
3. A sprinkler comprising a dome shaped chamber, a closure for the base of said chamber, an outlet orifice in the top of said chamber and centrally positioned therein, an inlet substantially tangential to said chamber adjacent to the

base of said chamber and at right angles to said outlet orifice, an annular flange surrounding said outlet orifice and extending centrally within the said dome, and an annular wall carried by said closure of greater diameter than said flange and extending inwardly of said dome to a position of overlap with said flange, said wall and said flange cooperating concentrically to form an annular passage between them, and said wall having a height sufficient to screen said passage from said inlet.

4. In a whirlpool sprinkler having a circular chamber, an inlet substantially tangential thereto, and an outlet centrally located in one end thereof, the combination of, a tubular member extending within said chamber from said outlet and adapted to screen said outlet from the adjacent portion of said chamber, and a member surrounding the interior end of said tubular member and forming therewith a restricted annular passage thereto and adapted to screen said passage from said inlet.

5. In a whirlpool sprinkler having a circular chamber, an inlet substantially tangential thereto, and an outlet centrally located in one end thereof, the combination of, a tubular member extending within said chamber from said outlet to a point adjacent the other end of the said chamber and adapted to divide the whirlpool into a first whirlpool within said chamber and outside of said tubular member and a second whirlpool within said tubular member in alignment with said outlet, and means for directing said first subdivided whirlpool into said second subdivided whirlpool at a velocity greater than the mean velocity of said first subdivided whirlpool.

6. A sprinkler comprising a circular chamber, an inlet to said chamber arranged substantially tangentially thereof, an outlet positioned centrally at one end of said chamber, and a tubular flange on said outlet extending centrally within said chamber to a point below the upper level of said inlet, whereby to maintain the center of rotation within said chamber in axial alignment with said chamber.
